UNITED STATES PATENT OFFICE.

SENECA R. STODDARD, OF GLENS FALLS, NEW YORK

ELECTRICAL TROLLEY.

SPECIFICATION forming part of Letters Patent No. 784,639 dated March 14, 1905.

Application filed March 21, 1903. Renewed August 12, 1904. Serial No. 220,517.

To all whom it may concern:

Be it known that I, SENECA R. STODDARD, a citizen of the United States, and a resident of Glens Falls, in the county of Warren and State 5 of New York, have invented a new and Improved Electrical Trolley, of which the following is a full, clear, and exact description.

My invention relates to electrical trolleys for general use, and more particularly to trolleys used in connection with so-called "third-rail systems."

I do not limit myself to any exact form of device for carrying out my invention, as the same may be constructed with various modifications, all coming within the scope of my invention. I give below a description of my preferred form, however, and leave to individuals the privilege of modifying the same according to their several tastes and needs.

Reference is to be had to the accompanying drawings, forming a part of this specification, in which similar characters of reference indicate corresponding parts in all the figures.

Figure 1 is a perspective view showing my invention as applied to a simple form of third-rail system. Fig. 2 is a side elevation of the trolley-shoe and its immediate connections. Fig. 3 is a fragmentary elevation, partly in section, of the contact mechanism; and Fig. 4 is a vertical section upon the line 4-4 of Fig. 3 looking in the direction of the arrow.

The ordinary track-rails are shown at 12 and the third rail at 3. Upon the truck-frame 4 is mounted a beam 5, which may be connected thereto in any suitable manner. Pivoted upon the beam 5 are a pair of curved bars 6 7 and a pair of straight bars 8 9. The trolley-shoe is shown at 10 and is pivotally connected to the bars 6, 7, 8, and 9. Another 40 pair of curved bars, 11 12, each provided with a slot 11^a, as indicated in Fig. 2, are pivotally connected at their respective upper ends with the beam 5. The slots 11^a slidably engage the respective pins 12^a 23. When the 45 shoe 10 is raised, the bars 6, 7, 8, and 9 cause it to move obliquely upward with a parallel motion, and as the bars 11 12 are free to slide relatively to the pins 12^a 23 they do not interfere at all with the movements of the shoe. 50 By this arrangement when the shoe is drawn

over an irregularity of the rail, such as a cross-rail or switch, it can move upward or downward and is free to conform to the surface of the rail. The curved or arc-shaped form of the bars 6 7 11 12 assists them in gliding gently over obstructions immediately adjacent to the rail.

Mounted upon the sides of the shoe 10 are longitudinal movable bars 13 and 20, provided at their ends with pivots 14 15. The inner surface of the bar 13 is curved, as indicated at 16 in Fig. 4. Mounted upon the lower edges of the shoe 10 are plates 17 17^a. The plate 17 is provided with an aperture 19 of frusto-conical shape, through which passes 65 a pin 23, carrying a spherical journal 18. The movable bar 20 is likewise provided with a curved surface 21, and mounted upon this bar and supported by a pivot-pin 12^a is a spherical journal 22, which is fitted into the plate 70 17^a. This plate 17^a is provided with an opening 25, analogous to the opening 19 in the plate 17. The pivot-pin 12^a terminates in a head 24, and the pivot-pin 23 terminates in a head 11^b. The purpose of the curved surfaces 75 16 21 is to allow more or less relative swinging movement as between the bars 13 20 and the shoe 10, this swinging movement taking place upon the spherical journals 18 22, considered as centers. Suppose, for instance, that by 80 an irregularity in the shape of the third rail or by a splinter resting accidentally upon the top thereof the shoe 10 chances to be twisted outwardly or inwardly, as the case may be, the play of the pins within the frusto-conical 85 apertures enables this erratic movement of the shoe to take place, the bars 13 and 20 moving one upwardly and the other downwardly a slight distance. Each of the spherical journals 18 22 therefore forms a sort of universal 90 joint with one of the bars 17 17^a, so as to render the local or rocking abnormal movements of the shoe independent of those of the bars.

Mounted within the third rail 3 is a longitudinal conductor 26, partially surrounded by an insulating-jacket 27, as indicated in Fig. 4. A rocking jaw 28 is pivoted at 29 within the shoe 10 and is provided with a contacting edge 30, which is free to engage the longitudu- 100

dinal conductor 26. This jaw 28 is provided with a mutilation 31^a, in which is a pin or crank 31, preferably integral with the jaw. An arm 32 is provided with a bifurcated end 33, which engages the pin 31, as indicated more particularly in Fig. 4. The arm 32 is pivoted at 34 and is integral with a plate 35.

The current is fed to the motor by means of a flexible conductor 36. A plate 37 is separated from the plate 35 by means of insulation 38, through which pass screws 39, these screws being provided with collars 40, of insulating material, so that any electrical communication between the plates 35 and 37 is prevented. The current is therefore unable to escape through the plate 37 to the third rail 3.

The invention is used as follows: The conductor 36 being connected with the car-motor in the usual manner, the weight of the shoe 10 causes the plate 37 to engage the top of the third rail 3. The arm 32 is thereupon thrown to the right, as indicated in Fig. 4, so that the jaw 28 is raised and the contacting surface 30 of the same is forced into gentle engagement with the longitudinal conductor 26. An electrical communication is thus established between the conductor 26 and the flexible conductor 36, whereby the motor is energized. Should the distance from the bottom of the conductor 26 and the top of the third rail 3 be variable from any cause, the jaw 28, acting solely under the influence of the weight of the shoe 10, is free to move upwardly or downwardly relatively to the shoe 10 and is therefore continuously kept in yielding engagement with the conductor 26. The curved surfaces 16 and 21 facilitate movements of the bars 13 and 20 relatively to the shoe 10, and said bars will have more or less swinging motion. The shape of the apertures 19 and 25, together with the spherical form of the journals 18 and 22, also contributes to the result and enables the shoe to move with comparative freedom. As the trolley-shoe 10 rides along the third rail it moves slightly with reference to the truck-frame, and the contact member 27 also moves slightly with reference to the general position of the shoe. The third bars 11 12 merely facilitate the guiding of the shoe when the car moves in a direction represented at the left in Fig. 1 and prevent the shoe from falling below a predetermined position.

The device above described has considerable flexibility and is not likely to get out of order. Having thus described my invention, I claim as new and desire to secure by Letters Patent—

1. In an electrical trolley system, the combination of a longitudinal conductor, a third rail for supporting the same, said third rail being provided with a bearing-surface, a shoe for moving along said third rail, a lever mounted within said shoe and free to move relatively thereto when actuated by the weight thereof, and also free to engage said bearing-surface, and a rocking member mounted within said

shoe and provided with a bearing-surface for engaging said conductor.

2. In an electrical trolley, the combination of a trolley-shoe to be moved relatively to a longitudinal conductor, contact mechanism connected with said shoe and free to engage said conductor, and mechanism for actuating said shoe relatively to said longitudinal conductor, said mechanism being connected with said shoe by means of universal joints for the purpose of permitting relative movements to take place between said shoe and said mechanism for actuating the same. 70 75

3. In an electrical trolley system, the combination of a longitudinal conductor, a member 80 for supporting the same, said member being provided with a bearing-track surface, a trolley-shoe disposed adjacent to said member, and contact mechanism mounted within said shoe and free to move relatively to the same 85 for the purpose of engaging said conductor when actuated by the weight of said shoe.

4. In an electrical trolley, the combination of a trolley-shoe, and a member mounted therein and movable laterally relatively thereto for 90 the purpose of engaging an electrical conductor.

5. In an electrical trolley, the combination of a gravity-operated trolley-shoe, and contact mechanism connected with said shoe and movable to engage a stationary conductor by the weight of said shoe. 95

6. In an electrical trolley - shoe, contact mechanism movable relatively thereto and acting automatically by gravity alone to make 100 and break connection with an electrical conductor.

7. In an electrical trolley, the combination of a trolley-shoe to be moved in the general direction of a longitudinal conductor, and 105 weight-controlled contact mechanism connected with said shoe for engaging and disengaging said longitudinal conductor.

8. In an electrical trolley, the combination of a trolley-shoe to be moved relatively to a 110 longitudinal conductor, and contact mechanism connected with said shoe and movable relatively thereto for engaging and disengaging said conductor.

9. In an electrical trolley system, the combination of a third rail provided with a longitudinal conductor, a trolley-shoe engaging said third rail and free to move longitudinally in the general direction thereof, and contact mechanism connected with said shoe and controllable by the weight thereof for engaging and disengaging said longitudinal conductor. 115 120

10. In an electrical trolley system, the combination of a third rail provided with a body portion and with a longitudinal conductor insulated therefrom, a trolley-shoe engaging said third rail and free to move longitudinally thereof, and contact mechanism connected with said shoe and controllable by the weight thereof, a portion of said contact mechanism being 125 130

- insulated from said shoe and provided with a surface free to engage said longitudinal conductor directly.
11. In an electrical trolley, the combination of a shoe to be moved relatively to a longitudinal conductor, and a weight-controlled contact member connected with said shoe and movable relatively thereto for engaging and disengaging said longitudinal conductor.
12. In an electrical trolley, the combination of a shoe to be moved in a general direction substantially parallel with a longitudinal conductor, a contact member connected with said shoe and movable relatively thereto for engaging and disengaging said conductor, and a lever connected with said contact member and actuated by the weight of said shoe for engaging and disengaging said longitudinal conductor.
13. In an electrical trolley system, the combination of a third rail provided with an upper bearing-surface and with a longitudinal conductor, a trolley-shoe adapted to move along said rail, and contact mechanism mounted within said shoe and movable relatively thereto, said contact mechanism being provided with a portion for engaging said upper bearing-surface and with a portion for engaging said longitudinal conductor.
14. In an electrical trolley, the combination of a trolley-shoe to be moved in the general direction of a longitudinal conductor, a contact member connected with said shoe and free to automatically engage and disengage said longitudinal conductor, and mechanism connected with said shoe and with said member for automatically causing said contact member to engage and disengage said longitudinal conductor.
15. In an electrical trolley, the combination of a trolley-shoe, a contact member mounted therein and movable relatively thereto, and a lever connected with said contact member for forcing the same into engagement with the conductor, said lever being also connected with said shoe and free to engage a longitudinal member along which said shoe is free to move.
16. In an electrical trolley system, the combination of a third rail provided with a conductor having its surface facing downward, a shoe movable in the general direction of said third rail and provided with a member mounted within said shoe and free to rock, said member being provided with a contact-surface below said surface facing downward and free to rise into engagement therewith.
17. In an electrical trolley, the combination of a trolley-shoe, and a movable member pivoted therein and controllable by the weight thereof for the purpose of engaging a stationary electrical conductor.
18. In an electrical trolley system, the combination of a shoe adapted to move along the rail, and a contact member connected with said shoe and free to rock relatively thereto when

actuated by the weight of said shoe, said contact member being for the purpose of engaging a conductor connected with said rail.

19. In an electrical trolley, the combination of a trolley-shoe provided with a collector movable relatively thereto, said collector being free to move into engagement with a contact-surface when said shoe is pressed into engagement with a bearing-surface.

20. In an electrical trolley, the combination of a trolley-shoe, and a contact member free to oscillate relatively thereto and controllable by the weight thereof for the purpose of engaging a stationary conductor.

21. In an electrical trolley system, the combination of a third rail, a trolley-shoe engaging the same and free to move longitudinally thereof, and contact mechanism connected with said shoe and controllable by the weight thereof, a portion of said contact mechanism being insulated from said shoe and provided with a surface free to engage said longitudinal conductor directly.

22. A trolley-shoe, comprising a member adapted to slide upon a rail and provided with contact mechanism movable relatively to said member and free to engage a contact-surface connected with said rail.

23. A trolley-shoe, comprising a traveling member adapted to move downward toward a mechanical contact-surface, and mechanism engaging said traveling member and said contact-surface, said mechanism being provided with a contact member for engaging a conductor.

24. In a trolley-shoe, a traveling member adapted to slide upon a rail and to be forced toward the same by its own weight, in combination with contact mechanism for engaging a conductor connected with said rail, said contact mechanism being connected with said traveling member and free to engage said rail and being controllable by the weight of said traveling member.

25. A trolley-shoe, comprising a traveling member adapted to move along a rail, said member being forced toward said rail by gravity, a contact member mounted upon said traveling member and movable relatively thereto for the purpose of engaging a contact-surface, and intermediate mechanism connected with said traveling member and with said contact member for the purpose of transferring motion from said traveling member to said contact member.

26. In a trolley-shoe, the combination of a member to be moved along a rail, and a collector connected with said member and adapted to swing laterally in a general direction crossing the length of said rail.

27. In an electrical trolley system, the combination of a shoe to be flexibly connected with a motor-car and free to slide upon a supporting third rail, a member pivoted within said shoe and facing downward for engaging

the trolley-surface of said rail, and a collector also pivoted within said shoe and free to move into contact with an electrical conductor connected with said supporting member.

- 5 28. In an electrical trolley system, the combination of a shoe flexibly connected with a motor-car, and adapted to travel along a bearing-rail, a member pivotally mounted within said shoe and actuated by downward pressure
10 of said shoe relatively to said rail, and a collector connected with said shoe and actuated by said member so as to swing laterally in a direction crossing the general length of said rail for the purpose of engaging a conducting-surface.
- 15 29. In an electrical trolley system, the combination of a shoe, a supporting member pivoted therein and movable relatively thereto, and a swinging collector connected with
20 said supporting member and adapted to make contact with a longitudinal conductor.
- 25 30. In combination with a motor-car and a bearing-rail, of a trailing-shoe and a collector pivoted therein for the purpose of forming contact with a longitudinal conductor.

31. In an electrical trolley system, the combination of a trolley-shoe, and a rocking member mounted therein, said member being provided with a contact-surface free to move into engagement with an electrical conductor attached to the side or overhanging flange of a supporting-rail.

32. In combination with a motor-car, a trailing shoe flexibly attached thereto and free to slide along upon a supporting third rail, a bearing member pivoted within said shoe and facing downward for engaging the upper surface of said rail and by virtue of such engagement forcing a collector, also pivoted within said shoe, into contact with an electrical conductor embedded in or attached to the side or under portion of the said supporting-rail.

In testimony whereof I have signed my name to this specification in the presence of two subscribing witnesses.

SENECA R. STODDARD.
